SPEED CONTROL MECHANISM

Lawrence S. Brown, Long Island City, N. Y., assignor to The Sperry Corporation, a corporation of Delaware

Application March 24, 1947, Serial No. 736,720

3 Claims. (Cl. 74—471)

1. This invention relates to driving means for paper box machines or the like having a plurality of elements which are to be driven at different speeds having selected ratios, and as for an object to provide speed control mechanism having means for simultaneously varying the speeds of the various driven elements while maintaining the selected speed ratios therebetween.

Another object is to provide a mechanism of the above type including hydraulic driving means with speed control mechanisms inter-related to produce the above results.

Another object is to provide driving means of the above type having a simple adjusting mechanism for adjusting the speed ratios to any desired value and for maintaining the selected ratio throughout the speed range of the machine.

Various other objects and advantages will be apparent as the nature of the invention is more fully disclosed.

The present invention is particularly applicable to a paper box folding and gluing machine of the type shown in the Staude Patent No. 2,349,204, dated May 16, 1944. This machine includes a folding and gluing section including belt conveyors which feed the folded and glued blanks at predetermined rates and a stacking mechanism including a separate belt conveyor to which the folded blanks are fed and stacked from the first conveyor. The stacked blanks are fed on the last conveyor through a drying zone wherein the glue is dried. The rate of feed of the stack conveyor belt is slower than that of the first conveyor belt and is selected to provide the necessary drying time. The ratio between the speeds of the two belts results in stacking the folded blanks on the slower conveyor belt with a certain overlap or shingling, the amount of overlap being a function of the speed ratio of the two belts. This operation is shown and described in connection with Fig. 2 of the above mentioned Staude patent and only so much thereof is shown in the present application as is necessary to an understanding of this invention.

The present invention provides hydraulic driving motors for driving the respective conveyor belts and control valves for controlling the speeds of the individual motors. The control valves are actuated by an interlocked control mechanism which is adapted to maintain a selected speed ratio between the rates of travel of the two belts regardless of the absolute speeds and is also provided with ratio adjustment which may be adjusted to provide any desired overlap.

Although the novel features which are charac-

teristic of this invention are pointed out more particularly in the claims, the nature of the invention will be better understood by referring to the following description taken in connection with the accompanying drawings in which a specific embodiment thereof has been set forth for purposes of illustration.

In the drawings:

Fig. 1 is a longitudinal section through a portion of the stacking machine showing the two feed belts;

Fig. 2 is a diagrammatic view showing the hydraulic drive mechanism and control valves;

Fig. 3 is a front elevation of the control mechanism on a larger scale; and

Fig. 4 is a section on the line 4—4 of Fig. 3.

For an illustration of one type of machine to which the present invention may be applied, reference is made to Fig. 1 which shows a portion

20 of the folded box blank feeding and stacking mechanism illustrated in the Staude patent above mentioned. In this figure the folded box blanks 10 are shown as conveyed by a lower conveyor belt 95 which is driven over a series of idler pulleys 96 by a drive pulley 97 mounted on a shaft 73. The blanks 10 are held against the belt 95 by an upper belt 98 which is driven by a drive pulley 99 mounted on a shaft 73'. The belt 98 is forced against the belt 95 by a pressure roller device 100, and a smaller roller 100' at the lower end of an adjustable arm 101 directs the folded blanks onto a slower moving stacker belt 102 where they are overlapped to form a continuously moving stack 103 in which the glued surfaces are pressed together by pressure devices, including a presser belt 104 and a presser roller 105, for a sufficient period of time for the glued parts to set. The stacker belt 102 is shown as driven by a driving roller 110 through beveled gears 111 from a drive shaft 112. The belt 102 passes over an adjustable idler pulley 113 which is mounted for adjustment in a slotted bracket 114 which is pivoted to a bracket 116 by a pin 117 and is adjustable by an arcuate rack 118 on an extension 119 of the bracket 114. The rack 118 engages an adjusting gear 120. The roller 105 is mounted on a pivoted bracket 121 and may be adjusted in elevation by a bracket 122 pivoted at 123 and carrying a segment rack 124 engaged by an adjusting gear 125

35 journaled in a fixed bracket 126.

40 The adjusting rod 101 for the upper belt 98 is secured in a bracket 130 pivoted at 131 to a fixed support 132 and carries at its upper end a roller 133. An idler roller 134 is mounted concentric with the pivot 131. A presser roller 136

is mounted on an arm 137 attached to the rod 101 and cooperates with the pulley 96 to apply pressure to the folded blanks 10.

The belt 95 is driven through beveled gears 140 from a drive shaft 141. The shafts 73 and 73' are geared together for driving the belts 95 and 98 in unison.

It is to be understood that the drive has been shown as applied to the pulleys 97 and 110 merely for purposes of illustration. The drive may of course be applied to any selected belt pulley, such as the pulley at the trailing end of the belts so as to hold the top runs of the belts under tension. This invention is concerned with the means for applying power to the drive shafts 112 and 141. The driven elements may be variously located as desired.

It is noted that the blanks 10 are stacked on the belt 102 due to the difference in speeds of the belts 95 and 102 and the amount of overlap of the various blanks in the stack 103 will depend upon the ratio of these speeds.

Referring now to Fig. 2, the shaft 112 is shown as driven by a low speed hydraulic motor 150 and the shaft 141 is driven by a high speed hydraulic motor 151. The fluid for driving the motors 150 and 151 is held in a reservoir 152. From this reservoir it is pumped through a pipe 153 by pumps 154 driven by a prime mover, such as the motor 155. The pumps 154 deliver the fluid under pressure through pipes 156 and 157 to control valves 158 and 159, respectively. The control valves 158 and 159 are actuated by shafts 160 and 161, respectively, to supply fluid at a variable rate through ducts 162 and 163, respectively, to the motors 150 and 151. Excess fluid is returned from the valves 158 and 159 through ducts 164 and 165 to the reservoir 152. Fluid from the motors 150 and 151 is returned to the reservoir 152 through pipes 166 and 167. The motors 150 and 151 are of a type such that their speed of operation is dependent upon the volume of the fluid supplied through the pipes 162 and 163. This in turn is controlled by the positions of the valves 158 and 159.

The valve 159 is controlled by the shaft 161 which is connected to a shaft 170 carrying a control handle 171. The valve 158 is controlled by the shaft 160 which is connected to a shaft 172 carrying a pointer 173.

The control mechanism for the shafts 170 and 172 is shown in Figs. 3 and 4. It will be noted that the shaft 170 carries a cam 175 against which a cam follower 176 rests. This cam follower is mounted on a bell crank 177 and is held against the surface of the cam 175 by a spring 178. The bell crank 177 is pivoted at 179 to a fixed point and is pivoted at 180 to a link 181. The link 181 is pivoted at 182 to an arm 183. The arm 183 is pivoted to swing about a fixed pin 184.

A plate 185 is pivoted for parallel movement to links 186 and 187 which in turn are pivoted about fixed pins 188 and 189 respectively. The link 187 is pivoted to the plate 185 by means of a pin 189 carried in a bracket 190 attached to the plate 185 by means of screws 191.

The arm 183 is provided with an elongated slot 195 in which a cross head 196 slides. The cross head 196 is adjusted along the slot 195 by means of a threaded shaft 197 journaled in brackets 198 and 199 carried by the arm 183 and having an adjusting handle 200. The cross head 196 carries a pin 201 which rides in the vertical slot 202 in the plate 185. The cross head 196 may be

provided with a pointer 205 registering with a scale 206 carried by the arm 183.

Link 186 is provided with an arm 210 carrying a segment rack 211 meshing with a segment gear 212 carried on and operating the shaft 172 as indicated by the position of the pointer 173 on a scale 213. For limiting the movement of the shaft 172 and the pointer 173 in the lefthand direction as seen in Fig. 3 a hook 215 is provided which is adapted to be hooked over a stud 216 when desired.

In the operation of the control linkage shown in Figs. 3 and 4 the handle 171 is set in accordance with the desired speed of the motor 151. The cam 175 through the follower 176 and the linkage 181 swings the arm 183 about the pivot pin 184 a selected amount. Movement of the arm 183 through the cross head 196 and the pin 201 causes a parallel movement of the plate 185. The ratio of the movement of the plate 185 to the movement of the arm 183 is determined by the position of the cross head 196 with respect to the slot 195. The cam 175 is so designed that the combined effect of the above described linkage is to shift the segment gear 211 and shaft 172 by amounts to cause the motor 150 to operate at rates which bear a predetermined constant ratio to the rate of the motor 151 regardless of the position of the control handle 171. This ratio is varied by varying the position of the cross head 196 which in turn is controlled by the adjusting knob 200 and may be registered by the pointer 205 on the scale 206.

Inasmuch as the overlap of the folded blanks in the stack 103 is determined by the speed ratio of the belts 95 and 102, the scale 206 may be graduated to read directly in the amount of overlap.

After the overlap has been set on the scale 206 by the adjusting knob 200 the rate of feed of the conveyors may be varied by the control handle 171. This will change the speeds of motors 150 and 151 as desired but will maintain the predetermined speed ratio and the predetermined overlap of the stacked blanks regardless of the conveyor speeds.

It may be desirable to stop the motor 151 or to operate this motor at a comparatively low speed for selected periods of time. At the same time it may be undesirable to stop the drive of the conveyor belt 102 completely as this would leave the stack 103 in the drying oven or other apparatus to which they are fed thereby. In order to prevent the belt 102 from being driven at a speed below a predetermined minimum speed the hook 215 may be placed over the stud 216. The apparatus will then be operated in the above described manner until the pointer 173 reaches a position such that the end of the hook 215 engages the stud 216. When this occurs further movement of the pointer 173 and its associated shaft 172 is prevented. If the handle 171 is moved to the left beyond the position at which the hook 215 engages the stud 216, the follower 176 is prevented from following the cam 175 and is held disengaged by the hook 215. Hence the motor 151 may be slowed down to any predetermined speed or may be stopped without stopping the motor 150 completely. Under this condition the stack 103 may be run out of the machine after which the motor 150 may be stopped by disengaging the hook 215 and allowing the pointer 173 and the shaft 172 to move to the extreme left position under the influence of the spring 178.

It will be noted that by means of the present invention the relative drive speeds of the two mo-

tors may be controlled simultaneously or selectively as desired and that any desired speed ratios may be maintained regardless of variations in the actual speeds of the two motors.

While the invention has been shown as applied to a particular type of box blank folding and stacking machine, it is to be understood that the control mechanism may be applied to any type of machine wherein two elements are to be driven under the relative conditions above mentioned and the invention is not to be restricted to the particular type of machine which has been indicated for purposes of illustration. Various changes and adaptations and further applications of the invention will be readily apparent to a person skilled in the art. The invention is only to be restricted in accordance with the scope of the following claims.

What is claimed is:

1. A mechanism for controlling the respective speeds of a pair of driven members having individual speed control elements, comprising a positioning means for each element, a settable member connected to control one of said positioning means, a linkage actuated by said settable member to set the other of said positioning means, said linkage including a cam member shaped to relatively position said speed control elements so as to maintain a constant speed ratio between said driven members for all settings of said settable member, a cam follower engaging said cam member, a pivoted arm actuated by said cam follower, a laterally shiftable member connected to actuate the other of said positioning members, means connecting said pivoted arm to actuate said laterally shiftable member with a parallel motion, and adjusting means connected to shift said connecting means with respect to the pivot point of said pivoted arm for varying said speed ratio.

2. A mechanism for controlling the respective speeds of a pair of driven members having individual speed control elements, comprising a positioning means for each element, a settable member connected to control one of said posi-

tioning means, a linkage actuated by said settable member to set the other of said positioning means, said linkage including a cam member shaped to relatively position said speed control elements so as to maintain a constant speed ratio between said driven members for all settings of said settable member, a cam follower engaging said cam member, a pivoted arm actuated by said cam follower, a member mounted for parallel movement, pivot means connecting said arm to shift said last member, and a link actuated by said last member to set said other positioning means.

3. A mechanism for controlling the respective speeds of a pair of driven members having individual speed control elements, comprising a positioning means for each element, a settable member connected to control one of said positioning means, a linkage actuated by said settable member to set the other of said positioning means, said linkage including a cam member shaped to relatively position said speed control elements so as to maintain a constant speed ratio between said driven members for all settings of said settable member, a cam follower engaging said cam member, a pivoted arm actuated by said cam follower, a member mounted for parallel movement, pivot means connecting said arm to shift said last member, a link actuated by said last member to set said other positioning means, and means adjusting the position of said pivot means along said arm to vary said speed ratio.
